UNITED STATES PATENT OFFICE.

FRANK ARCHIE GRAHAM, OF HARBOR SPRINGS, MICHIGAN.

LIFEBOAT APPARATUS.

Application filed August 13, 1920. Serial No. 403,375.

To all whom it may concern:

Be it known that I, FRANK ARCHIE GRAHAM, a citizen of the United States, and a resident of Harbor Springs, county of Emmet, and State of Michigan, have invented a new and Improved Lifeboat Apparatus, of which the following is a full, clear, and exact description.

This invention relates to an apparatus for use in life boats, and has reference more particularly to an apparatus for life boats which is adapted to actuate the propeller by compressed air, the heat from compressing said air being utilized in distilling salt water in vacuo.

When shipwrecked persons are adrift in a life boat, two of the essentials necessary are the production of distilled water for quenching thirst, and propelling means for the life boat to take same to land. It sometimes happens that persons have been adrift in a life boat on the ocean and have died a horrible death of thirst because the salt water was not fit to drink.

An object of this invention therefore, is to provide an apparatus which may be operated by the occupants of the life boat to furnish both distilled water and compressed air as power to operate the propeller.

Another object of this invention is to provide an apparatus of the class indicated in which the air compressor pump cylinder is cooled by salt water, the heat from said cylinder being utilized in distilling said salt water in vacuo so as to obtain drinking water.

A further object of this invention is to provide an apparatus in a life boat for the propulsion of said life boat and for the distillation of salt water which is manually operated and does not require fuel, thus increasing the capacity of the lift boat for passengers and food.

A further object of this invention is to provide an air compressor with a maximum volumetric efficiency due to cooling of the compressed air by the salt water to be distilled.

A still further object of this invention is to provide a vacuum pump to be used for distilling the salt water in vacuo with the lowest possible temperature so as not to cause inconvenience to the occupants of the life boat.

Reference is to be had to the accompanying drawing forming a part of this specification

in which it is understood that the drawing illustrates only one form of the invention, and in which

Figure 1 is a plan view of the life boat 60 fitted with my improved apparatus.

Figure 2 is a central sectional view through the life boat.

Figure 3 is a central sectional view through a unit of my improved apparatus 65 on a large scale.

Figure 4 is a sectional view through the apparatus on the line 4—4 of Figure 3.

Referring to the accompanying drawing by numerals 10 indicates a life boat having 70 center seats 11, bow seat 12, stern seat 13, and tiller 14. The life boat is also provided with a screw propeller 15 or other suitable driving mechanism mounted on a shaft 16, said shaft being rotated by a compressed air 75 motor 17 of any suitable construction. A compressed air tank 18 is positioned under the stern seat 13, and a pipe 19 having a valve 20 connects said tank to the motor 17.

In order to supply compressed air to the 80 tank 18, I provide a cylinder 21 having cylinder heads 22 and 23. An exhaust valve 24 and an intake valve 25 are positioned in or near the cylinder head 22, and a piston 26 having a flexible washer 27 of leather, rubber, or the like, is slidably mounted in the cylinder 21. A piston rod 28 is secured at one end to the piston 26 by means of nuts 29. The intake valve 25 is open to the atmosphere, and the outlet valve 24 opens into 90 a coil pipe 30 which in turn is connected to a pipe 31 leading to the air tank 18.

The compressed air passing through the coil 30 is warm due to the heat of compression, and I take advantage of this fact in 95 utilizing this heat for the distillation of the salt water in vacuo. In order to accomplish this, I position the coil 30 inside a vapor chamber 32 having a removable cover 33. A vacuum cylinder 34 is connected to the 100 vapor chamber 32 by a port 35, and a piston 36 is slidably mounted in the cylinder 34 and is provided with a flexible washer 37 of rubber, leather, or the like. A piston rod 38 is connected to the piston 36 by nuts 39. 105 The cylinder 34 is provided with a cylinder head 40 through which extends the end of the piston rod 38 opposite the piston 36, and said piston rod end is connected by a yoke 41 to the end of the piston rod 28 opposite 110 the piston 26, said yoke being connected to said piston rods by nuts 42. A hole 43 is

provided in the yoke 41 between the rods 28 and 38, and a link 44 is pivotally connected by a bolt 45 to said yoke, said bolt passing through the hole 43. The end of 5 the link 44 opposite the bolt 45 is pivotally connected by a bolt 46 to a lever 47 pivotally mounted in a bracket 48, said bracket being secured to the floor 49 of the life boat. The upper end of the lever 47 is provided with 10 a laterally extending handle 50 which is operated by the occupant of the life boat seated on one of the seats 11.

The rocking of the lever 47 by an occupant of the life boat causes pistons 26 and 15 36 to reciprocate in cylinders 21 and 34 respectively, thus causing the heated compressed air to pass through the coil 30 and a vacuum to be formed in the vapor cylinder 32. I provide a salt water tank 51 20 preferably positioned under the bow seat 12. A pipe 52 is connected to the tank 51 extending to within a short distance of the bottom of said tank. The pipe 52 extends 25 along the cylinder 21 to form a preheating coil 53, and the end of said pipe is provided with a metal valve 54 seated in a valve housing 55. The end of the pipe 53 extends into the vapor chamber 32 and is bent downwardly directly over the coil 30 so that when 30 a vacuum is created in the chamber 32, salt water will be drawn from the tank 51 and will fall on the coil 30 in the form of a spray or drops. The water falling on the coil 30 will be vaporized by the heat of the 35 compressed air due to the vacuum in the vapor chamber 32 and the steam will pass into the cylinder 34 through the port 35, while the salt remaining behind will fall on to a tray 56 which can be cleaned out from 40 time to time by removing the cover 33. A thimble 57 is positioned around the coil 30 so as to prevent the water from spreading, as it falls.

When the piston 36 (Fig. 3) moves to the 45 right, the water vapor in the right hand end of the cylinder 34 passes the washer 37 due to the fact that the periphery of said washer is turned to the left. When the piston 36 moves to the left, the water vapor in the 50 cylinder 34 is driven out through an outlet valve 58 into a condensing coil 59, said coil being under atmospheric pressure and serving to condense the vapor to water. Distilled water formed in the coil 59 is forced 55 upwardly through a pipe 60 into a water tank 61 preferably positioned under the bow seat 12. Both the tanks 51 and 61 are open to the atmosphere so as to obtain proper 60 action of the apparatus, and a spigot 62 is provided in the lower end of the tank 61 from which the drinking water may be drawn as needed.

In operation the occupant of the life boat 65 is seated on one of the seats 11 and operates the lever 47 by means of the handle 50. The

rocking of the lever 47 causes the pistons 26 and 36 to reciprocate in the cylinders 21 and 34 respectively so that compressed air is formed in the cylinder 21 passing through the outlet valve 24, the coil 30, the pipe 31, and the compressed air tank 18, while the piston 36 creates a vacuum in the vapor chamber 32. Salt water is drawn from the tank 51 through the pipe 52, preheating coil 53, and valve housing 55 on to the coil 30 70 in the form of drops or spray, said salt water being vaporized by the heat of the compressed air under the action of the vacuum in the chamber 32 so that the water vapor is forced out of the vapor chamber 32 and cylinder 34 by the piston 36, through the valve 58 and condensing coil 59. The vapor in the coil 59 condenses to water which is forced through the pipe 60 into the tank 61 and may be drawn from said tank through the spigot 62 from time to time for drinking 80 purposes. The salt remaining from the vaporization of the water drops into the tray 56 and may be cleaned out from time to time by removing the cover 33. The compressed air in the tank 18 operates the air motor 17 which causes the rotation of the propeller 15 thus driving the life boat to land.

It is understood that a number of my units are placed in the life boat so that each occupant of the life boat works to produce compressed air for operating the propeller and distilling water for drinking purposes. My apparatus is especially advantageous in that it is unnecessary to carry fuel to operate the propeller 15 and to distill the salt water for the preparation of drinking water. Thus the life boat can have a greater capacity for carrying passengers and food. Also the salt water is distilled in vacuo 100 at a low temperature so that the heat from the stills does not cause inconvenience to the occupants.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new and desire to secure by Letters Patent:

1. In a life boat apparatus, a chamber, a hollow member in the chamber, means for forcing compressed air into the said member whereby the member may be heated, a salt-water supply pipe extending into the chamber above the said member, and means for creating a vacuum in the said chamber, whereby salt-water will be drawn through said pipe and discharged upon said member.

2. In an apparatus of the class described, the combination with a life boat, of man-

- ually operated means for compressing air, manually operated means for creating a vacuum, means for distilling salt water in vacuo utilizing the heat of said compressed air, means for condensing the vapors of said salt water for use as drinking water, and means for propelling said life boat by the use of said compressed air.
3. In an apparatus of the class described, 10 the combination with a motor driven life boat, of a distilling apparatus comprising a vacuum chamber, manually operated means for simultaneously compressing an operating fluid for a motor and creating a vacuum 15 in said chamber, means for distilling water in the vacuum by utilizing the heat of said compressed fluid, and a fluid operated motor for propelling the boat.
4. In an apparatus of the class described, 20 the combination with a life boat, of a compressed air cylinder, a piston slidably mounted in said cylinder, means for manually reciprocating said piston in said cylinder so as to form compressed air, means for 25 manually creating a vacuum, means for distilling salt water in vacuo, utilizing the heat in said compressed air, means for condensing the steam from said salt water for use as drinking water, and means for utilizing 30 said compressed air for the propulsion of said life boat.
5. In an apparatus of the class described, the combination with a life boat, of a compressed air cylinder, a piston slidably mounted 35 in said cylinder, means for manually reciprocating said piston in said cylinder so as to form compressed air, means for manually creating a vacuum, means associated with said cylinder for preheating salt water utilizing the heat of the compressed air in said cylinder, means for distilling said salt water utilizing the heat of said compressed air, means for condensing the steam from said salt water for use as drinking water, and means for utilizing 40 said compressed air for the propulsion of said life boat.
6. In an apparatus of the class described, the combination with a life boat, of means for compressing air, pumping means for 45 creating a vacuum, means for manually actuating said air compressor and said vacuum pump, means for utilizing the compressed air formed by said air compressor for the propulsion of said life boat, means for distilling salt water in vacuo, utilizing the heat of said compressed air, and means for condensing the steam from said salt water for use as drinking water.
7. In an apparatus of the class described, 50 the combination with a life boat, of means for manually producing compressed air, a vapor chamber, means for passing said compressed air through a coil in said vapor chamber to a compressed air container, man- 55 ually actuated means for creating a vacuum in said vapor chamber, means for applying salt water to the outside of said coil so as to cause the vaporization of said salt water utilizing the heat in said compressed air, means for condensing the steam from said salt water to form drinking water, and means for propelling said life boat utilizing the compressed air in said container.
8. A device as described in claim 7 characterized by means associated with said air compressor means, adapted to preheat said salt water utilizing the heat of the compressed air before said salt water is applied to said coil.
9. A device as described in claim 7 characterized by means in said vapor chamber adapted to receive the salt formed as a residue from the distillation of said salt water.
10. In a life boat apparatus, a vacuum chamber, a compressor, a hollow member in the vacuum chamber and into which compressed air is delivered, and the member thereby heated, a salt water supply pipe extending into the vacuum chamber and discharging on to the said member, and means for producing a vacuum in said chamber and withdrawing the vapors therefrom.
11. In a life boat apparatus, an air compressor, a vacuum chamber, a coil in said chamber, and into which compressed air is forced, and the coil thereby heated and means for discharging salt water into said coil.
12. In a life boat apparatus, an air compressor, a vacuum chamber, a coil in the chamber heated by compressed air, means for discharging salt water in the form of a spray on the coil, and means for producing a vacuum in said chamber and withdrawing the vapors therefrom.
13. In a life boat apparatus, an air compressor, a chamber, a coil in the chamber and into which compressed air is forced whereby the coil may be heated, means for discharging salt water in the form of a spray on the coil whereby the spray may be vaporized, a pump connected with the said chamber for producing a vacuum therein and withdrawing the vapors therefrom, and a condensing coil connected with said pump.
14. The combination with a boat provided with a motor driven propeller, and means to compress an operating fluid for the motor, of a distilling apparatus comprising a vaporizing chamber, means for simultaneously operating the compressor and for drawing salt water into the vaporizing chamber, a compressed fluid manifold connecting the compressor and the motor and passing through said chamber, whereby heat of the compressed operating fluid serves to vaporize the water, and a condenser for said vaporizer.
15. The combination with a boat provided with a turbine driven propeller and means for compressing an operating fluid therefor,

of an evaporator comprising a vacuum chamber, means for manually operating the compressor and for creating a vacuum in said chamber simultaneously, means for admitting salt water to the chamber, and a manifold connecting the compressor and motor, and passing through the chamber whereby the heat of the operating fluid is utilized to vaporize the water in the chamber.

10

16. The combination with a motor boat having means for compressing an operating fluid for the motor, of an evaporator comprising a vacuum chamber, a compressed fluid conduit passing therethrough, and means for introducing a liquid into said chamber whereby the heat of the compressed fluid within the conduit will vaporize the fluid. 15

FRANK ARCHIE GRAHAM.
